UNITED STATES PATENT OFFICE.

ERIK NOREN, OF BELOIT, WISCONSIN.

IRONING-MACHINE.

SPECIFICATION forming part of Letters Patent No. 640,312, dated January 2, 1900.

Application filed January 18, 1899. Serial No. 702,570. (No model.)

To all whom it may concern:

Be it known that I, ERIK NOREN, a citizen of the United States, residing at Beloit, in the county of Rock and State of Wisconsin, have 5 invented certain new and useful Improvements in Machines for Turning Collars, of which the following is a specification.

The object of this invention is the production of an ironing-machine for turning collars embodying the several improvements hereinafter set forth.

In the accompanying drawings, Figure 1 is a perspective view of two ironing-machines, one for ironing roll or lay-down collars and 15 the other for turning the "wings" of standing collars. Fig. 2 is a side elevation, partly in section, of the pivoted ironing-arm, hereinafter designated by the letter E. Fig. 3 is a transverse section through the ironing-arm 20 of the machine for ironing lay-down collars on dotted line 3 3 of Fig. 2. Figs. 4 and 5 are detail views of a clamping device for holding the collar in position on the ironing-bed. Fig. 6 is a vertical central section of a 25 moistener-box, taken on the line 6 6, Fig. 7; and Fig. 7, a horizontal section of the same on dotted line 7 7 of Fig. 6. Fig. 8 is a longitudinal section through the outer end of the 30 sliding ironing-arm, hereinafter designated as the "ironing-arm" H. Fig. 9 is a detail view of the parts supporting the ironing-arm E.

Like letters of reference indicate corresponding parts throughout the several views.

In the construction of this machine I have 35 provided the supporting - column A, surmounted by a transversely - extending support, comprising the two oppositely-disposed arms A' and A². On the arm A' is mounted the form of this ironer adapted to turn roll 40 or lay-down collars, while the arm A² bears a device for turning the wings of the "wing" style of standing collar.

In the roll or turn-down collar ironing machine a vertical spindle B, screw-threaded 45 at its lower end, is held rigidly in position above its supporting-arm A' by the nut B'. A hand-wheel C is rotatably mounted on the vertical spindle B, and just above the wheel and rigidly connected therewith is provided 50 the circular ironing-bed C'. This ironing-bed C' is secured to the circular rim C², and the rim in turn is supported by the upwardly and

outwardly extending arms C³, which arms diverge from the hub C⁴. The circular ironing-bed C' is formed of a band of sheet metal 55 and is therefore quite thin. The ironing-bed C' and the hand-wheel C turn together upon the spindle B, the collar in the ironing operation being placed on the upper edge of the ironing-bed C'.

In order to prevent the slipping of the collar on the ironing-bed C', I have provided an angular or L-shaped clamping-arm C⁵, mounted by the pivot C⁶ on one of the arms C³. The clamping-arm C⁵ is also provided with 65 an elongated opening C⁷. The cam or eccentric lever C⁸ operates the clamping-arm C⁵, and for that purpose is mounted on the pivot C⁹ and has the stud C¹⁰ for entering and engaging the elongated opening of the clamping-arm C⁵ slightly eccentric to the pivot C⁹, 70 whereby a movement of the lever C⁸ actuates the clamping-arm C⁵.

A yoke D is pivotally mounted on the vertical spindle B at the upper end thereof, being secured in its position on said spindle by the cap D', affixed to the upper end of said spindle, and between the free arms of the said yoke D a tilting block D² is mounted upon the bolt D³, extending between said yoke-arms. The tilting block D² is provided with 75 the opening D⁴ therein.

D⁵ is a flat spring held in position on the yoke by the cap D', between which cap and yoke the spring lies, extending outward a little distance substantially at right angles to the vertical spindle B. The spring D⁵ supports the ironing-arm (to be next described) in a position elevated above the ironing-bed C' when ironing is not being done, the link 90 D⁶ forming the connection between the outer end of the spring D⁵ and the ironing-arm. E is the said ironing-arm. It has a bearing in the tilting block D², extending through the opening D⁴ in said block. Two stop-pins E' 95 limit the longitudinal movement of said ironing-arm E with relation to said tilting block D², one of which stop-pins E' is removable to provide for the withdrawal of the ironing-arm E from the tilting block.

The smoothing-iron on the ironing-arm E comprises two members, one of which, E², is formed integral with the ironing-arm, while the other, E³, is movably mounted thereon,

having a sliding engagement with said ironing-arm by virtue of an elongated opening E^4 in said member E^3 . The screw E^5 and the plate E^6 hold the sliding ironing member E^3 in place on the ironing-arm E . A spring E^7 tends to throw the movable member E^3 toward the ironing-bed, and the thumb-screw E^8 adjusts the tension of the spring. In the drawings the spring E^7 is shown to be at its greatest tension. It is relieved by unscrewing the thumb-screw E^8 , thus increasing the distance between the free ends of the said spring. The operator's handle E^9 , formed of some non-conducting material, as wood, is provided at the outer end of the ironing-arm E .

To heat the two-part smoothing-iron, I have provided a combustion-chamber E^{10} , which is a mere inclosure, into which the gas-flame from the heating-burner is directed.

E^{11} is a stud for supporting the fuel-pipe, and E^{12} a horn over which the ends of roll-collars are formed. The horn is heated by the flame within the combustion-chamber E^{10} .

Two perforated ears E^{13} , integral with the ironing-arm E , provide a means of pivotal attachment for the upper ends of the wire composing the link D^6 , the lower end of said link being surrounded by the free end of the flat spring D^5 .

F is a fuel-pipe, and F' the burner therein for the combustion-chamber E^{10} . The fuel-pipe F is fed from the two pipes F^2 and F^3 , the former for gas and the latter for air, as I have found that the mixture of the two creates a cleaner fire and heats with greater economy in gas consumption. The proportions of gas and air supplied to the flame are regulated by the valves F^4 and F^5 in the air and the gas pipes, respectively. Flexible rubber tubes (not shown) convey the gas and air under pressure to the flame.

In the form of ironing-machine here shown, adapted to turn the wings of wing-collars, the standard G is secured to and projects upwardly from the supporting-arm A^2 , having the inverted-V-shaped ironing-bed G' and the arm G^2 formed integral therewith. The arm G^2 is provided as a support for the guide-rod G^3 , which rod extends parallel with the ironing-bed G' .

H is an ironing-arm quite similar to the corresponding ironing-arm E . It has the bearing-sleeve H' on the guide-rod G^3 and the two-part smoothing-iron H^2 and H^3 , the latter member of which smoothing-iron is adapted to have a yielding movement to and from the ironing-bed G' . The former member H^2 of the smoothing-iron is made integral with the ironing-arm H , and the two members together conform to the uppersurface of the ironing-bed G' .

H^4 is an operating-handle for the ironing-arm H , and the threaded stem H^5 for said handle extends downward through an elongated opening H^6 , formed in said yielding ironing member H^2 , and, together with the plate H^7 and the nut H^8 , forms the means of attachment

between the said yielding member H^2 and the ironing-arm H . A tension-spring H^9 holds the said yielding member toward the ironing-bed G' and the thumb-screw H^{10} regulates the force of the spring, both of which are the same in form and function as the corresponding parts E^7 and E^8 hereinbefore described.

H^{11} is a combustion-chamber for the heating-flame, and H^{12} is a grooved smoothing-horn adjacent to the combustion-chamber H^{11} . The purpose of this smoothing-horn H^{12} is to make smooth the rough "saw" edges of worn collars and cuffs, the said edges being first moistened in the moistener-box (to be later described) and afterward ironed down smooth by being drawn several times through the groove of the horn H^{12} .

A stud H^{13} on the ironing-arm H supports a fuel-pipe I , provided with a burner I' for directing a flame into the combustion-chamber H^{11} . Both gas and air are supplied for the flame, as and for the purpose hereinbefore explained.

The sleeve connection between the ironing-arm H and the guide-rod G^3 permits the said ironing-arm to be raised above the ironing-bed G' when work is being placed on the said ironing-bed.

A receptacle J , containing a sponge J' and a quantity of liquid and provided with the cover J^2 , comprises the moistener-box hereinbefore mentioned. The cover J^2 of the box is provided with the two upwardly-extending lips J^3 , between which is the opening J^4 , through which opening the sponge J' projects. A sliding extension-arm J^5 is provided in the frame for supporting the moistener-box J , the outer end J^6 of which arm is made in dovetail form (in transverse section) to correspond with a groove J^7 at the side of the receptacle J , whereby the box may readily be removed from the said arm. A like wedging projection J^8 on the standard G provides a holder for the moistener-box when it is desirable to remove the box from the extension-arm J^5 .

In turning lay-down collars the collar is first folded along the proper line, placed upon the ironing-bed C' , secured in position by the clamping-arm C^5 , and gas being lighted and the irons E^2 and E^3 heated the hand-wheel C is grasped by the left hand of the operator and the handle E^9 by the right hand of the operator and the collar rotated under the moving ironing-surfaces. When the turned edge has been properly smoothed, the clamping-arm C^5 is released from engagement with the collar by depressing the cam-lever C^8 and the collar removed from the ironing-bed.

When the ironing-arm E is not pressed downward upon the ironing-bed C' by the hand of the operator, the spring D^5 holds it in an elevated position above the said ironing-bed C' .

If the collar is a roll-collar, the forward edges are formed on the horn E^{12} instead of being ironed upon the ironing-bed C' .

In operation the sliding member E^3 is held

against the outer face of the collar by the spring E⁷, and the tension of this spring is adjusted and regulated by turning the thumb-screw E⁸.

5 The ironing-arm E may be removed from the tilting block D² by removing the stop-pin nearest the end of the ironing-arm E.

I have found that a mixture of air and gas forms an efficient fuel and one free from dirt 10 and soot. The regulation of the proportions of gas and air is had by turning the valves F⁴ and F⁵ in the respective pipes F² and F³.

When wing-collars are to be ironed, the edges to be folded are moistened in the moistener J and the wing placed upon the ironing-bed G'. The irons H² and H³, having first been heated, are rubbed over the collar until a proper finish upon the wing is had.

I claim as my invention—

20 1. In an ironing-machine, in combination, a supporting-frame, an ironing-bed, and a two-part grooved iron, one of the parts of which iron has a yielding movement to and from the ironing-bed.

25 2. In an ironing-machine, in combination, a supporting-frame, an ironing-bed, an ironing-arm, and a two-part grooved iron, one part of which iron is fixed to the arm and the other has a yielding movement to and from the ironing-bed.

30 3. In an ironing-machine, in combination, a supporting-frame, an ironing-bed, a two-part grooved iron, one of the parts of which iron has a yielding movement to and from the ironing-bed, and a combustion-chamber adjacent to said two-part grooved iron.

35 4. In an ironing-machine, in combination, a supporting-frame, an ironing-bed, an ironing-arm, a two-part grooved iron, one part of which iron is fixed to the arm and the other has a yielding movement to and from the ironing-bed, and a spring for the last-mentioned part of the iron.

40 5. In an ironing-machine, in combination, a supporting-frame, an ironing-bed, an ironing-arm, a two-part grooved iron, one part of which iron is fixed to the arm and the other has a longitudinally-elongated opening, means for attaching the last-mentioned part of the iron to the arm, whereby it has a yielding movement to and from the ironing-bed, and a spring for the movable member of the iron.

45 6. In an ironing-machine, in combination, a supporting-frame, an ironing-bed, an iron for the bed, and a clamp for holding the fabric on the bed, which clamp comprises a pivoted clamping-arm having an elongated opening therein, a pivoted cam-lever, and a stud on said cam-lever for engaging the elongated opening in the clamping-arm.

50 7. In an ironing-machine, in combination, a supporting-frame, an ironing-bed, a two-part grooved iron one of the parts of which iron has a yielding movement to and from the ironing-bed, and means for holding the fabric on the ironing-bed.

55 8. In an ironing-machine, in combination,

a supporting-frame, an ironing-bed, a two-part grooved iron one of the parts of which iron has a yielding movement to and from the ironing-bed, and a clamp for holding the fabric on the bed, which clamp comprises a pivoted clamping-arm having an elongated opening therein, a pivoted cam-lever, and a stud on said cam-lever for engaging the elongated opening in the clamping-arm. 70

9. In an ironing-machine, in combination, a supporting-frame, a circular ironing-bed, a pivoted ironing-arm, a two-part iron on said arm, one of which parts has a yielding movement to and from the bed. 80

10. In an ironing-machine, in combination, a supporting-frame, a circular rotatable ironing-bed, a pivoted ironing-arm, a two-part grooved iron on said arm, one of which parts has a yielding movement to and from the ironing-bed, and a spring for said last-mentioned part of the iron. 85

11. In an ironing-machine, in combination, a supporting-frame, a spindle thereon, a circular ironing-bed rotatably mounted on said spindle, an ironing-arm pivotally mounted on the spindle, a two-part iron on said ironing-arm, one of which parts is fixed in its connection with the arm and the other has a yielding movement to and from the ironing-bed. 90

12. In an ironing-machine, in combination, a supporting-frame, a spindle thereon, a circular ironing-bed rotatably mounted on said spindle, supporting-arms for said ironing-bed, a clamping-arm for engaging fabric on the ironing-bed, pivotally mounted on one of said supporting-arms, which clamping-arm has an elongated opening near one of its ends, a cam-lever pivoted to said supporting-arm and having a stud eccentric with respect to the pivot of said cam-lever, which stud is adapted to engage the elongated opening of the clamping-arm, and an ironing-arm also pivotally mounted on the said spindle. 95

13. In an ironing-machine, in combination, a supporting-frame, a spindle thereon, a circular ironing-bed rotatably mounted on said spindle, a hand-wheel for rotating the bed, an ironing-arm pivotally mounted on the spindle, a two-part iron on said ironing-arm, one of which parts is formed integrally with said arm and the other has a yielding movement to and from the ironing-bed, a spring for the last-mentioned part of said iron, and a combustion-chamber adjacent to the iron. 100

14. In an ironing-machine, in combination, a supporting-frame, a spindle thereon, a circular ironing-bed rotatably mounted on said spindle, a hand-wheel for turning the ironing-bed, a yoke pivotally mounted on the spindle, a tilting block pivotally mounted between the arms of the yoke, an ironing-arm having a sliding engagement with said tilting block, a two-part grooved iron, a combustion-chamber on the ironing-arm, adjacent to the iron, and a burner in the chamber. 105

15. In an ironing-machine, in combination,

a supporting-frame, a spindle thereon, a circular ironing-bed rotatably mounted on said spindle, a yoke pivotally mounted on the spindle, a tilting block pivotally mounted between the arms of the yoke, an ironing-arm having a sliding engagement with said tilting block, a spring in said yoke, a connection between

the spring and the ironing-arm, a combustion-chamber on said ironing-arm, and a burner in the combustion-chamber.

ERIK NOREN.
